UNITED STATES PATENT OFFICE

ROY HOUGHTEN, OF DETROIT, MICHIGAN

RECEPTACLE FOR REFUSE

Application filed July 25, 1927. Serial No. 208,345.

This invention relates generally to receptacles for refuse such as garbage, ashes and the like and consists of certain novel features of construction, combinations and arrangements of parts as will be more fully described and particularly pointed out in the appended claims.

In the accompanying drawings:

Figure 1 is a front elevation of a receptacle embodying my invention.

Figure 2 is an end elevation thereof.

Figure 3 is a top plan view thereof.

Figure 4 is a horizontal sectional view through the same when installed in a wall of a building or the like.

Figure 5 is a front elevation of a slightly modified construction.

Figure 6 is a vertical sectional view through the construction shown in Figure 5.

Referring now to the drawings, 1 is the base, 2 and 3 respectively are the front and rear walls, 4 is the top wall and 5 and 6 respectively are the end walls of a receptacle embodying my invention. Located between the end walls 5 and 6 and preferably parallel thereto is a vertical partition 7 that is preferably connected into the base 1 and top wall 4 and thereby divides the receptacle into the laterally spaced chambers or compartments *a* and *b* respectively. As shown, the front wall 2 preferably inclines rearwardly from the base to the top wall 4 and is provided with three spaced openings 8, 9 and 10 respectively

which constitute an outlet opening for the compartment A and outlet and inlet openings for the compartment B. The top wall 4 is preferably parallel to the base 1 and has a single opening 11 that constitutes the inlet opening for the compartment A. Any suitable means such as the covers 12, 13, 14 and 15 respectively may be used to close the openings 8, 9, 10 and 11. As shown these covers are preferably formed of metal and are connected by suitable hinges 16, 17, 18 and 19 respectively to the walls of the receptacle. Preferably the front and top walls 2 and 4 respectively of the receptacle have openings formed therein to receive the hinge parts so that the assembly operation will be simplified. Inasmuch as the wall 2 inclines upwardly and

rearwardly and the hinges are connected thereto at the upper edges of the openings, it will be readily apparent that the gravity will cause the metal covers to be normally closed. Hence, the need of separate fasteners has been obviated. Preferably wedge-shaped ledges 20, 21 and 22 respectively are provided on the front wall 2 at the upper edges of the openings 8, 9 and 10 respectively to prevent water from draining through the openings into the receptacle. Due to their location these ledges will limit the opening movement of the covers, hence they will prevent the covers from leaning back against the wall 2 above the openings and thus being accidentally left in open position. To facilitate the removal of refuse from the receptacle, the base 1 is preferably provided at the forward edge thereof with an inclined portion 23 that extends upwardly to the lower edges of the openings 8 and 9 respectively. As shown, the base 1, walls 2, 3, 4, 5 and 6, partition 7 and ledges 20, 21 and 22 respectively are preferably formed of reinforced concrete. In the process of construction, these parts are formed and integrally connected together in one operation by placing a sufficient supply of concrete and suitable reinforcing means such as metal scraps or rods in a sectional mold (not shown). Thus the receptacle may be termed a one piece construction when the mold sections are removed.

In use, the receptacle is preferably anchored in a suitable opening in a wall of a building. As shown, the upper forward edge of the front wall 2 of the receptacle is preferably arranged flush with the outer face of the building wall 25 so that the inlet opening 11 in the top of the receptacle is located and accessible inside of the building. To prevent any intruder entering the building through the receptacle, the cover 15 may be provided with a suitable lock, (not shown).

In Figures 5 and 6 I have shown a slight modification in which the inlet opening 30 for the compartment A is located in the front wall 31 of the receptacle instead of in the top wall 32. With this construction the hinges 33 for the cover 34 are connected to the wall 31 above the opening 30 and are

protected by a wedge-shaped ledge 35 which corresponds and functions similar to the ledges 20, 21 and 22 respectively.

Thus from the foregoing description, it will be readily apparent that I have provided a strong and durable construction that can be manufactured at a comparatively low cost. As the receptacle is cast into one piece it will also be apparent that the installation thereof has been greatly simplified. In fact 10 they may be built and shipped as units ready for immediate installation. Moreover leakage due to faulty joints has been obviated entirely.

While it is believed that from the foregoing description, the nature and advantage of my invention will be readily apparent, I desire to have it understood that I do not limit myself to what is herein shown and described and that such changes may be resorted to when desired as fall within the scope of what is claimed.

What I claim as my invention is:

1. A receptacle for refuse having an upwardly inclined wall provided with an opening for refuse, a closure for the opening hingedly connected to the wall above the opening, a ledge overhanging said opening so as to protect the connection between the closure and wall and prevent water draining through the opening into the receptacle, said ledge being constructed and arranged to limit the opening movement of the closure so as to prevent the latter from leaning back 30 against the inclined wall above the opening and thereby accidentally be left in open position.

2. A receptacle for refuse having an upwardly inclined wall provided with an opening for refuse, a closure for said opening hingedly connected to said wall above the opening, and means upon said inclined wall protecting the connection between the closure and wall, preventing water draining through the opening into the receptacle, and limiting the opening movement of the closure 40 to prevent the closure when in open position from leaning back against said wall and accidentally remaining in open position.

50 In testimony whereof I affix my signature.

ROY HOUGHTEN.
